UNITED STATES PATENT OFFICE

127,435

DESIGN FOR A TEXTILE FABRIC

Emil Lambert, Farnham, Quebec, Canada, assignor to Collins & Aikman Corporation, Philadelphia, Pa., a corporation of Delaware

Application March 29, 1941, Serial No. 100,010

Term of patent 14 years

To all whom it may concern:

Be it known that I, Emil Lambert, a citizen of the United States, residing in Farnham, Province of Quebec, Dominion of Canada, have invented a new, original, and ornamental Design for a Textile Fabric, of which the following is a specification, reference being had to the accompanying drawing, forming part thereof. The figure is a plan view of a piece of textile fabric embodying my new design.

The design is characterized by spaced apart parallel chain-like rows, the alternate rows

showing relatively large links and short connecting bars and the intervening rows showing small links and long connecting bars, the links and bars of adjacent rows being in staggered relation, the spaced apart parallel chain-like rows being separated by parallel straight rows, substantially as shown.

I claim:

The ornamental design for a textile fabric, as shown and described.

EMIL LAMBERT,
